UNITED STATES PATENT OFFICE.

SAMUEL W. FISH, OF PLAINFIELD, NEW JERSEY, ASSIGNOR TO TAYLOR IRON & STEEL COMPANY, OF HIGH BRIDGE, NEW JERSEY, A CORPORATION OF NEW JERSEY.

SAFE OR VAULT DOOR.

997,795.

Specification of Letters Patent. Patented July 11, 1911.

Application filed August 26, 1910. Serial No. 578,994.

To all whom it may concern:

Be it known that I, SAMUEL W. FISH, a citizen of the United States, residing at Plainfield, in the county of Union and State 5 of New Jersey, have invented certain new and useful Improvements in Safe or Vault Doors, of which the following is a specification.

This invention relates to safes or vaults, 10 and especially to safe or vault doors particularly adapted for use where the safe or vault is of massive construction, the object of the invention being to provide improved means for holding and securing the door within the 15 doorway of the vault body.

In vault doors as usually constructed it has been the practice to secure the door holding means, as for instance the bolt carrying frame, to the door by means of bolts 20 or screws passing through such bolt frame and projecting into the inner face of the door. It is a well known fact that although such bolted frames and the large bolts usually used for securing such frames to the 25 door are very impressive in appearance, the strength of such construction is nevertheless dependent upon the means, or bolts, for attaching such bolt frame to the door, so that the entire door holding means is no stronger 30 than the bolts or screws which secure the frame to the door. It is also well understood that a door having integral holding means, as for instance lugs, now in common use, provide ideal security, but in order to 35 use such a holding means it is necessary to have a rotary door or else to mount on the jamb of the body an internally serrated annulus, neither of which, however, is considered ideal for large safe and vault doors 40 owing, in the first instance, to the friction between the surface of the door and the jamb, and in the second instance, because the means for rotating the annulus must be mounted on the jamb.

The object, therefore, of the present improvement is to provide a door holding means having all of the good features of the lug door and without any of its objectionable features when applied to large doors, 50 and to accomplish this I have provided a member carrying door holding lugs which may be rotated independently of the door instead of rotating the entire door, so that a non-rotating door may be used while at the 55 same time securing it against the opening

thereof by lugs, and which lugs will be so attached to the door that the resisting strength thereof will be equal to lugs which are formed integral with the door. Thus I am enabled to provide, as hereinbefore 60 stated, a door which can be secured in position by the use of lugs while avoiding rotation of the door in the jamb of the body.

In the drawings accompanying and forming part of this specification, Figure 1 is a 65 rear view of this improved door, a part thereof being broken away and in section; Fig. 2 is a sectional view taken in line 2—2, Fig. 1; Fig. 3 is a cross-sectional view of the rotating member of the door; Fig. 4 is a 70 cross-sectional view of the non-rotating member or door proper; Fig. 5 is a detail sectional view of a portion of the door looking in the direction of the arrow shown in Fig. 4; Fig. 6 is a detail view of a portion 75 of one of the holding bolts; and Fig. 7 is a view of a portion of the body jamb.

Similar characters of reference indicate corresponding parts throughout the figures 80 of the drawings.

In the present improvement the door is made up of a pair of members, one a non-rotating member and comprising the door proper or door body 2 and the other a rotatable member 3 carrying means for securing and holding the door in the doorway or jamb 60 of the body 70, which jamb carries the door holding lugs 80. These two door members are suitably secured together by means hereinafter described, whereby they 85 may be moved as a unitary structure in opening or closing the door, while permitting the member 3 to be rotated independently of the door for the purpose of securing the door in the jamb. These members may be made up in various forms, but in the form shown the door 2 is shown as a 90 round or annular door comprising a body portion or main web 4 having a rearwardly extending flange 5 inclosing a chamber and provided with annular shoulders or steps 6 and 7 adapted to engage similarly formed shoulders or steps carried by the jamb. The periphery of the door is shown as of tapered 95 formation, and the annular flange 5 is provided at its inner end with interiorly located spaced apart lugs 8. The exterior surface of the flange is provided with recesses 9 adjacent to the inner end thereof, the inner 100 ends of which recesses open at the end of the 110

flange, each recess thus having a pair of end walls and a front wall for the purpose hereinafter set forth.

The member 3, which may be made in any desired manner, is provided with lugs 10 cooperating with the lugs 8 of the member 2, whereby the two members are securely held together. This member 3 is also provided with lugs 11 adapted to engage similarly 10 formed lugs carried by the vault body adjacent to the jamb thereof for securing the door in position, and therefore these lugs will be hereinafter termed door holding lugs, as contradistinguished from the lugs 8 15 which secure the two members together, and which will be hereinafter termed member holding lugs. The lugs 11, when the member 3 is properly rotated to secure the door in its jamb, are in position to form the inner 20 walls of the recesses 9 and thus prevent the withdrawal of the door from the body, while the walls of the recesses 9 prevent the rotation of the door within the body. That is to say, when the member 3 is rotated into 25 such position that the spaces between the lugs 11 are in register with the recesses 9 of the door flange it will be apparent that the door can be swung into its jamb so that the lugs on the door jamb will enter between 30 the lugs 11 of the member 3 and into the recesses 9 of the door flange, the circumferential end walls of such recesses preventing rotation of the door member 2 but not the rotation of the member 3, such jamb lugs 35 being of a size to properly fit the recesses 9 of the door flange. Then when the member 3 is rotated to carry the spaces between the lugs 11 out of register with the recesses 9 and the lugs 11 into position to register with 40 such recesses, the lugs 80 of the body jamb fitting therein at this time will securely hold the door against withdrawal.

The door holding lugs 11 have about half the circumferential length of the member 45 attaching lugs 8 and 10 to permit the rotating member 3 to be rotated from locked to unlocked position and vice versa without disengaging the two members 2 and 3 of the door. The rotating member 3 is rotatably 50 mounted on a boss or cylindrical projection 12 at the center of the door, suitable anti-friction bearings 13 being provided between the cylindrical projection 12 and the cylindrical projection 14 of the member 3. In 55 practice the rotating member 3 is constructed of the form shown in section to provide increased strength.

For locking the member 3 to the door member 2, and to prevent rotation of the member 3 at a predetermined time, suitable means is provided, which consists in the present instance of locking bolts 15. Any desired number of these bolts may be used, two or more. In the present instance the 60 rotating member 3 is provided with a pair

of annular spaced apart flanges 16 and 17 having bolt apertures therein for the reception of the bolts 15, the flanges 16 and 17 thus constituting guides for the bolts. The ends of the bolts are adapted to project 70 into the bolt openings formed in the flange 5 of the door member 2. In the present construction the bolts are shown located entirely around the rotating member 3, although, as hereinbefore stated, a less number thereof could be used. By this means the rotating member is locked to the door member 2 when the lugs 11 are in position to engage the jamb lugs 80 of the body. At this time the bolts are in position to register with their openings in the flange 5 of the door member 2 and can be shot into position by any suitable means provided for that purpose, either automatically or otherwise, and so prevent the rotation of the member 85 3 and the unlocking of the door.

In the present instance the means for operating the bolts carried by the rotating member comprises a suitable gear mechanism under the control of a suitable automatic 90 and time-lock mechanism. The rotating member 3 carries a plate or disk 18 for supporting the gear mechanism for operating the bolts. This mechanism comprises a large central gear 19 mounted on a stud 20 95 supported by the plate 18, suitable anti-friction bearings 21 being placed between the stud and the hub of the gear. In mesh with this gear are a series of pinions 22, one for each bolt, and mounted on a stud 23 100 secured to the plate 18. Secured to the inner end of each bolt is a link or lever 24 having an elongated slot 25 through which the stud 23 projects, this elongated slot being provided to permit the retraction and protraction of the bolt. Each of the gears or pinions 22 is provided with a pin 26 projecting into an elongated opening 27 of the link 24, so that as the pinion is rotated by the large central gear it will protract or retract the bolts in a manner which will be 105 readily understood.

As hereinbefore stated, various means may be used for rotating the large central gear thereby to shoot or withdraw the bolts, but in the present instance this gear is under the control of a suitable automatic and time-lock mechanism such as is in common use. The automatic 30 and time lock 31 are mounted on a plate 32 supported by 110 studs 33 projecting from the plate 18. The automatic is operatively connected with a rack bar 34, it being effective to reciprocate this bar in one direction on being set and in the opposite direction automatically. This 115 rack bar is in engagement with a pair of pinions 22', so that when the bar is shifted the pinions will be rotated and thereby the central gear rotated to rotate the pinions 22 and protract or retract the bolts. 120 125 130

In operating this mechanism the time lock is first wound and then the automatic bolt operating device 30 properly set, at which time the door is ready for closing. It is necessary, however, to provide means for releasing the automatic thereby to permit the same to shift the rack bar and so protract the bolts as soon as the rotative member 3 is rotated into locked position by the means hereinafter described. For this purpose a lever 35 is provided, see Fig. 1, in position to come in contact with a projection 81 on the inner face of the body jamb during the rotation of the member 3. This lever is so positioned and connected as to release a catch 36, which in turn allows the rack bar 34 to be forced by the protracting springs of the automatic into such position as to rotate the gears or pinions 22' and therethrough the central gear and thereby the pinions 22 and so protract the locking bolts and thus lock the rotative member 3 and the door member 2 together against rotation of the member 3 independently of the door. It will be understood of course that various means might be used, as hereinbefore stated, for protracting and retracting the bolts. In the present construction, when the time lock has run down the automatic will automatically shift the rack bar in the opposite direction and so retract the bolts and permit the rotation of the member 3 by the means provided for that purpose, to unlock the door. It will also be understood that the rotation of this member 3 may be controlled by a suitable combination lock such as is known as a day lock.

For rotating the member 3 to carry the lugs thereof into position to lock the door against withdrawal and to also carry the locking bolts 15 in position to lock the two members 2 and 3 together, suitable means may be provided, automatic or otherwise. In the present instance this means comprises a spindle 40 projecting through the door web and in position to be operated by a suitable crank. The inner end of this spindle carries a geared nut 41 in mesh with a geared segment 42 carried by the flange 17 of the rotating member 3, whereby, on rotating the spindle, the member 3 will be rotated to carry its lugs into or out of position to register with the lugs of the body jamb and into position to permit the bolts 15 to register with the openings in the flange 5 of the door member 2, or out of position to register therewith as the case may be. This geared nut 41 will be keyed to the spindle in any suitable manner. Thus it will be observed that by rotating the spindle 40 the member 3 will be rotated, together with its locking bolts and door holding lugs, and all of the mechanism designed to operate the bolts and control the operation thereof relatively to the door proper, so that the door

may be swung into and out of the doorway and securely held within the jamb of the body without the necessity of rotating the massive structure, while it will be as securely held by the provision of holding lugs 70 as though such lugs were formed integral with the door and the door rotated to engage the lugs carried thereby with the jamb lugs. By the provision of this improved door it will be immediately apparent that 75 the door proper may be made of unmachineable metal while the rotating member may be made of a machineable metal, thus very much facilitating the construction and setting up of the operating parts, as well as 80 very materially lessening the cost thereof. Furthermore, it will also be observed that the locking bolts 15 are so located that the ends thereof are protected by the flange 5, so that it would be an impossibility to force 85 nitro-glycerin into the door joint and against the ends of the bolts in order to retract the same, since the bolts and the ends thereof are entirely protected against any action of explosives at the door joint, as the 90 ends of the bolts do not project through the flange or to the exterior surface thereof.

In practice some suitable non-conducting material 50 may be located between a plate 51 and the web 4 of the door. The bolt operating mechanism will also be covered in practice with a suitable glass covering, in the usual manner, to keep dirt and dust from the mechanism, and this covering may be provided with a hinged door 54 to give 100 access to the bolt operating mechanism and the time lock and automatic.

It will be understood, of course, that instead of operating the bolts 15 by an automatic in the manner shown various other 105 ways, as by means of spindles, could be provided for this purpose if preferred, so that the bolt operating mechanism may be considered either as a full automatic, as semi-automatic, or one entirely controlled 110 by spindles from the outside, as may be preferred.

In practice, instead of mounting the rotative member 3 centrally of the member 2 in the manner shown, it will be obvious that suitable antifriction bearings might be located between the flange 17 and the flange 5 of the door, and thus the central bearing of this rotating member 3 entirely done away with. The bolt openings in the flange 5 will be provided with soft metal inserts in the usual manner.

From the foregoing it will be observed that I am able to provide a door which may be secured within its doorway by holding lugs without the necessity of rotating a massive door, thus combining with an ordinary swinging non-rotating member or door all the advantageous features of one secured in position by lugs.

I claim as my invention:

1. In a door of the class described, the combination of a rotatable and a non-rotating member having coöperating lugs for securing the members together for movement as a unitary structure, means for locking said members against independent rotation at one time, and means for rotating one of said members relatively to the other at another time to effect the unlocking and locking of the door within its jamb. 5
2. In a door of the class described, the combination of a rotatable and a non-rotating member having coöperating lugs for securing the members together for movement as a unitary structure, means for locking said members against independent rotation at one time and comprising bolts, and means for rotating one of said members relatively to the other at another time to effect the unlocking and locking of the door within its jamb. 10
3. In a door of the class described, the combination of a rotatable and a non-rotating member having coöperating lugs for securing the members together for movement as a unitary structure, means for locking said members against independent rotation at one time and comprising bolts, automatically operative mechanism for operating said bolts, and means for rotating one of said members relatively to the other at another time to effect the unlocking and locking of the door within its jamb. 15
4. In a door of the class described, the combination of a rotatable and a non-rotating member having coöperating lugs for securing the members together for movement as a unitary structure, means for locking said members against independent rotation at one time, and means including a spindle for rotating one of said members relatively to the other at another time to effect the unlocking or locking of the door within its jamb. 20
5. In a door of the class described, the combination of a rotatable and a non-rotating member having coöperating lugs for securing the members together for movement as a unitary structure, means for locking said members against independent rotation at one time and comprising bolts, mechanism for operating said bolts, means for rotating one of said members relatively to the other at another time to effect the unlocking or locking of the door within its jamb. 25
6. In a door of the class described, the combination of a rotatable and a non-rotating member having coöperating lugs for securing the members together for movement as a unitary structure, means for locking said members against independent rotation at one time and comprising bolts, and means for preventing the operation of said bolts. 30
7. In a door of the class described, the combination of a rotatable and a non-rotating member having coöperating lugs for securing the members together for movement as a unitary structure, means for locking said members against independent rotation at one time and comprising bolts, mechanism for operating said bolts, means for rotating one of said members relatively to the other at another time to effect the unlocking or locking of the door within its jamb, and automatically operative means for preventing the operation of said bolts. 35
8. A door of the class described, comprising a rotatable and a non-rotating member, means for locking them together against independent rotation at one time, and means for rotating the rotatable member at another time, said rotatable member having means for holding the door in its doorway. 40
9. A door of the class described, comprising a rotatable and a non-rotating member, means for locking them together against independent rotation at one time, means for rotating the rotatable member at another time, said rotatable member having means for holding the door in its doorway, and means for preventing when locked together the rotation of said members within the doorway. 45
10. A door of the class described, comprising a rotatable and a non-rotating member, means for locking them together against independent rotation at one time, means for rotating the rotatable member at another time, said rotatable member having means for holding the door in its doorway, and means including a lug or lugs for preventing when locked together the rotation of said members within the doorway. 50
11. A door of the class described, comprising a rotatable and a non-rotating member, means for locking them together against independent rotation at one time, means for rotating the rotatable member at another time, said rotatable member having means for holding the door in its doorway, and means for preventing when locked together the rotation of said members within the doorway and comprising a lug and a recess for the reception of said lug, one carried by the door and the other by the jamb. 55
12. A door of the class described, comprising a rotatable and a non-rotating member, means for locking them together against independent rotation at one time, means for 60

- rotating the rotatable member at another time, said rotatable member having means for holding the door in its doorway, and means for preventing when locked together the rotation of said members within the doorway and comprising a lug and a recess for the reception of said lug, the lug being carried by the safe body and the recess by the door.
13. A door of the class described, comprising a rotatable and a non-rotating member, means for locking them together against independent rotation at one time, means for rotating the rotatable member at another time, said rotatable member having means for holding the door in its doorway, and means for preventing when locked together the rotation of said members within the doorway and comprising a recess or recesses carried by the non-rotating member for the reception of a lug or lugs carried by the vault body.
14. A door of the class described, comprising a rotatable and a non-rotating member, means for locking them together against independent rotation at one time, means for rotating the rotatable member at another time, said rotatable member having lugs coöperating with lugs carried by the body for holding the door in its doorway, and means comprising a recess or recesses and a lug or lugs, one carried by the door and the other by the body, for preventing the rotation of the rotatable and non-rotating members as a unitary structure within the doorway.
15. A door of the class described, comprising a rotatable and a non-rotating member, means for locking them together against independent rotation at one time, means for rotating the rotatable member at another time and including a spindle, a gear mounted thereon and a gear segment carried by the rotatable member, said rotatable member having lugs coöperating with lugs carried by the body for holding the door in its doorway, and means comprising a recess or recesses and a lug or lugs, one carried by the door and the other by the body, for preventing the rotation of the rotatable and non-rotating members as a unitary structure within the doorway.
16. A door of the class described, comprising a rotatable and a non-rotating member, means for locking them together against independent rotation at one time and comprising a bolt or bolts and means for shifting such bolt or bolts, means for rotating the rotatable member at another time, said rotatable member having lugs coöperating with lugs carried by the body for holding the door in the doorway, and means comprising a recess or recesses and a lug or lugs, one carried by the door and the other by the body, for preventing the rotation of the rotatable and non-rotating members as a unitary structure within the doorway.
17. A door of the class described, comprising a rotatable and a non-rotating member, means for locking them together against independent rotation at one time and comprising a bolt or bolts, means for shifting such bolt or bolts and including automatically operated means, means for rotating the rotatable member at another time, said rotatable member having lugs coöperating with lugs carried by the body for holding the door in the doorway, and means comprising a recess or recesses and a lug or lugs, one carried by the door and the other by the body, for preventing the rotation of the rotatable and non-rotating members as a unitary structure within the doorway.
18. A door of the class described, comprising a rotatable and a non-rotating member, means for locking them together against independent rotation at one time and comprising a bolt or bolts, means for shifting such bolt or bolts and including automatically operated means and time-lock mechanism, means for rotating the rotatable member at another time, said rotatable member having lugs coöperating with lugs carried by the body for holding the door in the doorway, and means comprising a recess or recesses and a lug or lugs, one carried by the door and the other by the body, for preventing the rotation of the rotatable and non-rotating members as a unitary structure within the doorway.
19. A door of the class described, comprising a rotatable and a non-rotating member, means for locking them together against independent rotation at one time and comprising a bolt or bolts, means for shifting such bolt or bolts and including automatically operated means and time-lock mechanism, means for rotating the rotatable member at another time and comprising a spindle, a gear mounted thereon and a gear segment carried by the rotatable member, said rotatable member having lugs coöperating with lugs carried by the body for holding the door in the doorway, and means comprising a recess or recesses and a lug or lugs, one carried by the door and the other by the body, for preventing the rotation of the rotatable and non-rotating members as a unitary structure within the doorway.
20. A door of the class described, comprising a non-rotating member comprising a web and a rearwardly extending flange, a rotatable member fitting within said flange, coöperating lugs for holding said members together, said rotatable member also having lugs for holding the door in its doorway, means for rotating said rotatable member, and means for locking said members together for movement as a unitary structure.

rotating members together for movement as a unitary structure and comprising a bolt or bolts and means for operating said bolts.

30. A door of the class described, comprising a non-rotating member having a rearwardly extending flange carrying interiorly located lugs, a rotatable member having two sets of lugs, one coöperating with the interiorly located lugs of the flange to hold the two members together as a unitary structure and the other set of lugs co-operating with lugs carried by the body for holding the door within its doorway, said door having recesses for the reception of the body lugs for preventing the rotation of said non-rotating member within the doorway, means for rotating the rotatable member, means for locking the rotatable and non-rotating members together for movement as a unitary structure and comprising a bolt or bolts, and means for operating said bolt or bolts and comprising an automatic.

31. A door of the class described, comprising a rotatable and a non-rotating member, means for rotating the rotatable member, said rotatable member having means for holding the door in its doorway, means for locking the members together against independent rotation and comprising bolts, means for preventing the rotation of said members when locked together within the doorway, and means for shifting said bolts and comprising a gear, a pinion in mesh therewith and connected with each of said bolts and means for operating said gear and comprising an automatic.

32. A door of the class described, comprising a rotatable and a non-rotating member, means for rotating the rotatable member, said rotatable member having means for holding the door in its doorway, means for locking the members together against independent rotation and comprising bolts, means for preventing the rotation of said members when locked together within the doorway, means for shifting said bolts and comprising a gear, a pinion in mesh therewith and connected with each of said bolts, means for operating said gear and comprising an automatic, and a rack bar connected with said automatic and with one or more of said pinions.

33. A door of the class described, comprising a rotatable and a non-rotating member, means for rotating the rotatable member, said rotatable member having means for holding the door in its doorway, means for locking the members together against independent rotation and comprising bolts, means for preventing the rotation of said members when locked together within the doorway, means for shifting said bolts and comprising a gear, pinions in mesh therewith and connected one with each of said bolts, means for operating said gear and

comprising an automatic, a rack bar connected with said automatic and with one or more of said pinions, and means operative on the closing of the door for permitting the operation of the automatic.

34. A door of the class described, comprising a rotatable and a non-rotating member, means for rotating the rotatable member, said rotatable member having means for holding the door in its doorway, means for locking the members together against independent rotation and comprising bolts, means for preventing the rotation of said members when locked together within the doorway, means for shifting said bolts and comprising a gear, pinions in mesh therewith and connected one with each of said bolts, means for operating said gear and comprising an automatic, a rack bar connected with said automatic and with one or more of said pinions, means operative on the closing of the door for permitting the operation of the automatic, and time-lock mechanism for controlling the movement of the automatic.

35. A door of the class described, comprising a non-rotating member comprising a body portion and a rearwardly extending flange having interiorly located lugs, and a rotatable member having two sets of lugs, one coöperating with the lugs of the flange for holding the two members together and the other coöperating with lugs of the body for holding the door in its doorway, the first set of lugs having greater circumferential length than the last set of lugs.

36. A door of the class described, comprising a non-rotating member comprising a body portion and a rearwardly extending flange having interiorly located lugs, a rotatable member having two sets of lugs, one set coöperating with the lugs of the flange for holding the two members together and the other set coöperating with the lugs of the body for holding the door in its doorway, the first set of lugs having greater circumferential length than the last set of lugs, said door having recesses for the reception of the lugs of the body to prevent the rotation of the non-rotating member within the doorway.

37. A door of the class described, comprising a non-rotating member comprising a body portion and a rearwardly extending flange having interiorly located lugs, a rotatable member having two sets of lugs, one set coöperating with the lugs of the flange for holding the two members together and the other set coöperating with lugs of the body for holding the door in its doorway, the first set of lugs having greater circumferential length than the last set of lugs, said door having recesses for the reception of the lugs of the body to prevent the rotation of the members within the doorway,

and means for preventing at a predetermined time the rotation of the rotatable member relatively to the non-rotating member.

- 5 38. A door of the class described, comprising a non-rotating member consisting of a body and a rearwardly extending flange having interiorly located lugs, a rotatable member rotatable within said flange and
10 provided with lugs coöperating with the lugs of the flange for holding the members together, said rotatable member also having lugs adapted to coöperate with lugs carried by the body for holding the door within its
15 doorway, means for rotating the rotatable member, bolts carried by the rotatable member for projection into the flange of the non-rotating member to prevent the rotation of said rotatable member at a certain
20 time, means for shifting said bolts and comprising pinions connected with the bolts and carried by the rotatable member, a gear also carried by the rotatable member and in mesh with said pinions, and means for operating said gear and comprising time-lock and automatic mechanism. 70

25 39. A door of the class described, comprising a non-rotating member consisting of a body and a rearwardly extending flange having interiorly located lugs, a rotatable member rotatable within said flange and provided with lugs coöperating with the lugs of the flange for holding the members together, said rotatable member also having lugs adapted to coöperate with lugs carried by the body for holding the door within its doorway, means for rotating the rotatable member, bolts carried by the rotatable member for projection into the flange of the non-rotating member to prevent the rotation of said rotatable member at a certain time, means for shifting said bolts and comprising pinions connected with the bolts and carried by the rotatable member, a gear also carried by the rotatable member and in mesh with said pinions, and means for operating said gear and comprising time-lock and automatic mechanism. 80

30 40. A door of the class described, comprising a non-rotating member consisting of a body and a rearwardly extending flange having interiorly located lugs, a rotatable member rotatable within said flange and provided with lugs coöperating with the lugs of the flange for holding the members together, said rotatable member also having lugs adapted to coöperate with lugs carried by the body for holding the door within its doorway, means for rotating the rotatable member, bolts carried by the rotatable member for projection into the flange of the non-rotating member to prevent the rotation of said rotatable member at a certain time, means for shifting said bolts and comprising pinions connected with the bolts and carried by the rotatable member, a gear also carried by the rotatable member and in mesh with said pinions, and means for operating said gear and comprising time-lock and automatic mechanism, and a rack bar connected with said automatic mechanism and
45 in mesh with some of said pinions. 85

40 41. In a door of the class described, the combination of a rotatable and a non-rotating member having means for securing the members together for movement as a unitary structure, means for rotating the rotatable member, door holding lugs carried by the rotatable member and adapted to coöperate with lugs carried by the body, said non-rotating member having recesses for the reception of the body lugs thereby to prevent the rotation of said member within the doorway, the door holding lugs of the rotatable member overlapping the body lugs when seated within the recesses of the door. 90

45 42. In a door of the class described, the combination of a rotatable and a non-rotating member having means for securing the members together for movement as a unitary structure, means for rotating the rotatable member, door holding lugs carried by the rotatable member and adapted to coöperate with lugs carried by the body, said non-rotating member having recesses for the reception of the body lugs thereby to prevent the rotation of said member within the doorway, the door holding lugs of the rotatable member overlapping the body lugs when seated within the recesses of the door, and means for locking the rotatable and non-rotating members together. 95

50 43. In a door of the class described, the combination of a non-rotating member constructed to fit the jamb of a safe and a rotatable member, carrying means for holding the door within its doorway, and coöperating means carried by the members and operative to permit or prevent rotation of the rotatable member relatively to the non-rotating member at different times respectively. 100

55 44. In a door of the class described, the combination of a non-rotating member constructed to fit the jamb of a safe, a member rotatable within the non-rotating member and carrying means for holding the door within its doorway, means for rotating the rotatable member, and coöperating means carried by the members and operative to permit or prevent rotation of the rotatable member relatively to the non-rotating member at different times respectively. 110

60 45. In a door of the class described, the combination of a non-rotating member, a member rotatable relatively to said non-rotating member and carrying means for holding the door within its doorway, means for rotating the rotatable member, and coöperating means carried by the members and operative to permit or prevent rotation of the rotatable member relatively to the non-rotating member at different times respectively. 115

65 46. In a door of the class described, the combination of a non-rotating member, a member rotatable relatively to said non-rotating member and carrying means for holding the door within its doorway, means for rotating the rotatable member, and coöperating means carried by the members and operative to permit or prevent rotation of the rotatable member relatively to the non-rotating member at different times respectively. 120

70 47. In a door of the class described, the combination of a non-rotating member, a member rotatable relatively to said non-rotating member and carrying means for holding the door within its doorway, means for rotating the rotatable member, and coöperating means carried by the members and operative to permit or prevent rotation of the rotatable member relatively to the non-rotating member at different times respectively. 125

75 48. In a door of the class described, the combination of a non-rotating member, a member rotatable relatively to said non-rotating member and carrying means for holding the door within its doorway, means for rotating the rotatable member, and coöperating means carried by the members and operative to permit or prevent rotation of the rotatable member relatively to the non-rotating member at different times respectively. 130

tating member, said members having co-operating lugs for holding them together and said rotatable member having door holding lugs adapted to coöperate with body lugs for holding the door within its doorway.

46. In a door of the class described, the combination of a non-rotating member, a member rotatable within said non-rotating member, said members having coöperating lugs for holding them together and said rotatable member having door holding lugs adapted to coöperate with body lugs for holding the door within its doorway, and means carried by the door and body for preventing the rotation of the non-rotating member within the doorway.

47. In a door of the class described, the combination of a non-rotating member, a member rotatable within said non-rotating member, said members having coöperating lugs for holding them together and said rotatable member having door holding lugs adapted to coöperate with body lugs for holding the door within its doorway, and means carried by the door and body for preventing the rotation of the non-rotating member within the doorway, said means comprising recesses carried by the door and into which the lugs of the body are adapted to seat.

48. In a door of the class described, the combination of a non-rotating member, a member rotatable within said non-rotating member, said members having coöperating lugs for holding them together and said rotatable member having door holding lugs adapted to coöperate with body lugs for holding the door within its doorway, means carried by the door and body for preventing the rotation of the non-rotating member within the doorway, said means comprising recesses carried by the door and into which the lugs of the body are adapted to seat, bolts for locking the members together, and means for shifting said bolts.

49. In a door of the class described, the combination of a non-rotating member, a member rotatable within said non-rotating member, said members having coöperating lugs for holding them together and said rotatable member having door holding lugs adapted to coöperate with body lugs for holding the door within its doorway, means carried by the door and body for preventing the rotation of the non-rotating member within the doorway, said means comprising recesses carried by the door and into which the lugs of the body are adapted to seat, bolts for locking the members together, means for shifting said bolts, and means for rotating the rotatable member.

50. In a door of the class described, the combination of a non-rotating member, a member rotatable within said non-rotating member,

said members having coöperating lugs for holding them together and said rotatable member having door holding lugs adapted to coöperate with body lugs for holding the door within its doorway, means carried by the door and body for preventing the rotation of the non-rotating member within the doorway, said means comprising recesses carried by the door and into which the lugs of the body are adapted to seat, bolts for locking the members together, means for shifting said bolts, and means for rotating the rotatable member and including a spindle carried by the non-rotating member.

51. In a structure of the class described, the combination of a body having lugs for holding the door against withdrawal, and a door having rigid means coöperating with said lugs of the body for preventing rotation of the door.

52. In a structure of the class described, the combination of a body having door holding lugs, and a door having means coöperating with the lugs of the body for preventing rotation of the door and comprising recesses for the reception of said body lugs.

53. In a structure of the class described, the combination of a body having door holding lugs, and a door having means coöperating with the lugs of the body for preventing rotation of the door and comprising recesses for the reception of said body lugs, said door comprising a non-rotating member and a rotatable member interlocked together for movement as a unitary structure.

54. In a structure of the class described, the combination of a body having door holding lugs, and a door having means coöperating with the lugs of the body for preventing rotation of the door and comprising recesses for the reception of said body lugs, said door comprising a non-rotating member and a rotatable member interlocked together for movement as a unitary structure and said rotatable member having lugs also coöperating with the body lugs for holding the door within its doorway.

55. In a structure of the class described, the combination of a body having door holding lugs, a door having means coöperating with the lugs of the body for preventing rotation of the door and comprising recesses for the reception of said body lugs, said door comprising a non-rotating member and a rotatable member interlocked together for movement as a unitary structure and said rotatable member having lugs also coöperating with the body lugs for holding the door within its doorway, and means for locking the rotatable and non-rotating members together.

56. In a structure of the class described, the combination of a body having door holding lugs, a door having means coöperating with the lugs of the body for prevent-

- ing rotation of the door and comprising recesses for the reception of said body lugs, said door comprising a non-rotating member and a rotatable member interlocked together for movement as a unitary structure and said rotatable member having lugs also coöperating with the body lugs for holding the door within its doorway, means for locking the rotatable and non-rotating members together and comprising bolts, and means for operating said bolts. 57. In a structure of the class described, the combination of a body having door holding lugs, a door having means coöperating with the lugs of the body for preventing rotation of the door and comprising recesses for the reception of said body lugs, said door comprising a non-rotating member and a rotatable member interlocked together for movement as a unitary structure and said rotatable member having lugs also coöperating with the body lugs for holding the door within its doorway, means for locking the rotatable and non-rotating members together and comprising bolts, means for operating said bolts, and means for rotating the rotatable member relatively to the non-rotating member. 58. In a structure of the class described, the combination of a body having door holding lugs, a door having means coöperating with the lugs of the body for preventing rotation of the door and comprising recesses for the reception of said body lugs, said door comprising a non-rotating member and a rotatable member interlocked together by lugs for movement as a unitary structure and said rotatable member having lugs also coöperating with the body lugs for holding the door within its doorway, means for locking the rotatable and non-rotating members together and comprising bolts, means for operating said bolts, and means for rotating the rotatable member relatively to the non-rotating member. 59. In a structure of the class described, the combination of a body having door holding lugs, a door having means coöperating with the lugs of the body for preventing rotation of the door and comprising recesses for the reception of said body lugs, said door comprising a non-rotating member and a rotatable member interlocked together by lugs for movement as a unitary structure, the member holding lugs having greater circumferential length than the door holding lugs whereby the door may be released from the body without the separation of the rotatable and non-rotating members, said rotatable member having lugs also coöperating with the body lugs for holding the door within its doorway, means for locking the rotatable and non-rotating members together and comprising bolts, means for operating said bolts, and means for rotating the rotatable member relatively to the non-rotating member. 60. A door of the class described, comprising a pair of members one rotatable relatively to the other, means for securing the members together against separation, similarly formed means carried by one of said members for securing the door to the body and released on the rotation of the rotatable member to permit the door to be withdrawn, means for rotating said member, and means for preventing the rotation of the non-rotating member relatively to the rotatable member at a predetermined time. 61. A door of the class described, comprising a pair of members one rotatable relatively to the other, means for securing the members together against separation, means carried by one of said members for securing the door to the body and released on the rotation of the rotatable member to permit the door to be withdrawn, means for rotating said member, and bolts carried by one of said members and coöperating with the other for preventing the rotation of the non-rotating member relatively to the rotatable member at a predetermined time. 62. A door of the class described, comprising a pair of members one rotatable relatively to the other, means carried by the rotatable member for securing the door to the body and released on the rotation thereof to permit the door to be withdrawn, means for rotating said member, and means carried by one of said members and coöperating with the other for preventing the rotation of the non-rotating member relatively to the rotatable member at a predetermined time. 63. A door of the class described, comprising a pair of members one rotatable relatively to the other, interlocking lugs carried by the members for securing them together against separation, lugs carried by the rotatable member and adapted to cooperate with similarly formed lugs carried by the body for holding the door within such body, and means for preventing the rotation of one member relatively to the other at a predetermined time. 64. A door of the class described, comprising a pair of members one rotatable relatively to the other, interlocking lugs carried by the members for securing them together against separation, lugs carried by the rotatable member and adapted to cooperate with similarly formed lugs carried by the body for holding the door within such body, and means for preventing the rotation of one member relatively to the other at a predetermined time, the lugs carried by the rotatable member having less circumferential length than the interlocking lugs carried by the members for securing them together.

65. In a door of the class described, the combination of a non-rotating member, a member rotatable relatively to said non-rotating member, said members having operating lugs for holding them together and said rotatable member having door holding means adapted to coöperate with means carried by the body for holding the door within its doorway.
